[57] ABSTRACT

An explosive composition which will withstand temperature exposure and temperature shock at supersonic speeds and upon environment exposure. It consists essentially of a high explosive pre-coated with a polyester resin consisting of the polyester portion of Laminac 4116 and 4134 admixed with vinyl toluene, alpha-methyl styrene and diallyl phthalate.

3 Claims, No Drawings

PLASTIC BONDED EXPLOSIVE COMPOSITION

The invention herein described may be manufactured and used by or for the Government of the United States of America for governmental purposes without the payment of any royalties thereon or therefor.

The invention relates to an improved castable plastic bonded explosive composition and its preparation capable of withstanding temperature exposure and temperature shock at supersonic speeds and upon environmental exposure.

Castable plastic-bonded explosive formulations developed up to the present time have shown energy characteristics similar to those of Composition B, a British developed composition during the period between World Wars I and II and which was standardized by the United States early in World War II. Composition B is a TNT-based composition and it has been considered a desirable and worthwhile goal to attempt to improve the explosive potential of the plastic-bonded types to exceed that of the best TNT-based formulations and still retain the desirable physical properties of the former. The present invention provides a formulation superior to the aforementioned conventional TNT-based explosives not only in respect to their resistance to melting at high temperatures but also in regard to physical properties and ease of processing.

The general purpose of this invention, therefore, is to provide an explosive composition for a missile warhead which can withstand the environment at the supersonic speeds to which the warhead will be subjected.

An object of this invention is to provide an explosive composition which can be used in applications involving aerodynamic heating.

Another object of this invention is to provide an explosive composition which has a reduced exotherm, is less brittle than other plastic bonded explosives, and resists cracking.

Yet another object of this invention is to provide an explosive composition which has the economic advantages of savings in time and materials used.

Other objects and the attendant advantages of this invention will be readily appreciated as the same become better understood by reference to the following detailed description.

The invention contemplates incorporating a polyester resin-coated explosive selected from the group consisting of cyclotrimethylenetrinitramine (RDX), cyclotetramethylenetrinitramine (HMX), diaminotrinitrobenzene (DATB) and others with a binder composition consisting essentially of vinyl toluene, alpha-methyl styrene and diallyl phthalate. The explosive is pre-coated with a mixture of unsaturated polyester resin sold under the tradename Laminac EPX 147-1 by American Cyanamid Company.

In preparing the formulation the liquids consisting of vinyl toluene, alpha-methyl styrene and diallyl phthalate were added to a mixing kettle then the resin-coated explosive was added and the mixture stirred until the resin dissolved and the explosive dispersed. Vacuum is usually applied to the kettle during the last portion of the mixing operation to remove entrapped air. When thoroughly mixed the batch was catalyzed. The catalyst-accelerator combination used consisted of methyl ethyl ketone peroxide in the form of 60% solution in dimethyl phthalate and cobalt naphthenate solution (6% cobalt as metal). The amounts of catalyst-

accelerator may be adjusted to produce the desired "pot life" of the composition. Acceptable results have been obtained using 0.1% cobalt naphthenate solution and 0.5% methyl ethyl ketone peroxide solution (based on binder weight of the batch).

It is important to use this particular catalyst combination, since the use of other catalyst systems in particular, t-butyl perbenzoate, will cause the diallyl phthalate to enter into the polymerization reaction rather than 10 acting as a plasticizer and the resulting product will lack flexibility and low shrinkage characteristics. After the catalyst has been mixed in, the material is cast into preforms or molds and allowed to stand at room temperature until gelled and cured. Heat may be applied to 15 accelerate curing, the temperature being limited by the nature of the explosive filler.

The explosive composition should have as high an explosive content as possible, being limited by the practical consideration of processability and explosive sensitivity.

The following formulation has a detonation velocity of 8060 m/sec in 1½ inch-diameter and an impact sensitivity of 36 cm (as compared to Composition B's 33 cm).

Ingredients	Percent by weight
30 Cyclotetramethylenetrinitramine (HMX)	83
Binder	17
The binder composition consisted essentially of	
Ingredients	Percent by weight
35 Unsaturated styrene free polyester resin (Laminac EPX 147-1)	42.4
Vinyl toluene	33.1
Alpha-methyl styrene	2.0
Diallyl phthalate	22.5

40 For applications where a lower detonation velocity is acceptable or desired, the binder content may be increased.

In preparing the binder, diallyl phthalate may range from 20 to 25 percent of the binder composition. Above 25% the product is too weak and below 20% it is not sufficiently flexible. When omitted from the binder, the solubility characteristics of the binder are altered to the point where phase separation occurs. The vinyl toluene contributes to reducing the shrinkage of the cross-linked polyester, but produces a vigorous exotherm. In combination with alpha-methyl styrene, the polymerization is controlled and a negligible exotherm results. The alpha methyl styrene content may vary between 2-5%, the 2% level being adequate without slowing down the reaction excessively.

Small samples of the explosive composition were prepared using 17, 20, 25 and 22.5% diallyl phthalate. The sample using 22.5% diallyl phthalate in the binder showed minimum cracking.

60 The percentage binder is important to the viscosity and processability of the composition. A total binder content of 17% produced a better detonation velocity than Composition B. Less binder than this would make it too difficult to process on a large scale and more binder would decrease its energetic properties.

Two pound samples of the present formulation and several similar formulations were cured nearly adiabat-

ically and their temperature rises were recorded. The formulation set out above exhibited an exotherm of approximately 5° F. While the other plastic-bonded explosives showed as much as 100° F. rise.

The combination of vinyl toluene, alpha-methyl styrene and diallyl phthalate as a binder for unsaturated, styrene free polyester resin coated high explosives is new and the composition produced has superior physical properties. The diallyl phthalate, a potentially reactive monomer, acts as a solubilizing agent and plasticer. 5

The Laminac unsaturated polyester resin EPX 147-1 which is used to pre-coat the high explosive before mixing with the liquid binder in the formulations described herein is manufactured by American Cyanamid. It is a monomer free polyester resin consisting of a blend of 15 the reaction products of adipic acid, maleic acid with diethylene glycol and phthalic acid, maleic acid with propylene glycol. The method of preparing the reaction products is fully described in U.S. Pat. No. 2,255,313, issued Sept. 9, 1941, which discloses preparation by reacting an alpha, beta-ethylenically unsaturated dicarboxylic acid and a glycol with or without a dicarboxylic acid free of non-benzenoid unsaturation.

The binder consisting essentially of unsaturated polyester resin, vinyl toluene, alpha-methyl styrene and diallyl phthalate is potentially useful for propellants and pyrotechnics formulations. 25

Obviously many modifications and variations of the present invention are possible in the light of the above teachings. It is therefore to be understood that within 30 the scope of the appended claims the invention may be practiced otherwise than as specifically described.

What is claimed is:

1. The plastic bonded explosive composition consisting essentially of

Ingredients	Percent by weight	40
A high explosive Binder	83 17	

said explosive being a member selected from the group consisting of cyclotetramethylenetrinitramine, cyclotrimethylenetrinitramine, and diaminotrinitrobenzene;

said binder consisting of 42.4% of a blend of the reaction products of adipic acid, maleic acid with diethylene glycol and phthalic acid, maleic acid with propylene glycol; 33.1% vinyl toluene; 2% alpha-methyl styrene; and 22.5% diallyl phthalate.

2. The process for the preparation of the composition of claim 1 which comprises

- pre-coating said high explosive with a blend of the reaction products of adipic acid and maleic acid with diethylene glycol, and phthalic acid and maleic acid with propylene glycol;
- mixing together vinyl toluene, alpha-methyl styrene and diallyl phthalate to form a homogeneous liquid binder;
- stirring said pre-coated explosive into said binder until the resin is dissolved and the explosive is dispersed thereby forming a mixture;
- catalyzing said mixture with a solution of cobalt naphthenate and methyl ethyl ketone peroxide;
- casting said catalyzed mixture into molds; and
- curing said mixture at room temperature until a solid product forms.

3. A binder formulation consisting essentially of the following:

Ingredients	Percent by weight
A blend of adipic acid and maleic acid with diethylene glycol, and phthalic acid and maleic acid with propylene glycol	42.4
Vinyl Toluene	33.1
Alpha-methyl styrene	2.0
Diallyl phthalate	22.5
